ATTORNEYS-

UNITED STATES PATENT OFFICE.

ROBERT S. HISLOP, OF RACINE, WISCONSIN, ASSIGNOR TO RACINE CONFECTIONERS MACHINERY COMPANY, OF RACINE, WISCONSIN, A CORPORATION OF WISCONSIN.

DEPOSITOR.

Application filed April 3, 1925. Serial No. 20,523.

My present invention has for its object an improvement in machines commonly known as chocolate depositors which are employed in the manufacture of chocolates and other forms of candy articles which are made from plastic material by its ejection through nozzles or orifices. The machine embodying my invention is preferably, although not necessarily, of the general type shown and 10 described in the patent to Demerath No. 791, 611, June 6, 1905.

A particular object of the invention is to provide in a machine of this character improved ejecting or depositing mechanism 15 the measuring elements of which can be quickly and conveniently removed from the machine and replaced by other measuring elements adapted to measure and deposit articles of different sizes. It will be understood that in the past, in order to measure and deposit, for example, chocolate buds or drops and also long chocolate bars, it was necessary to have different depositing machines for each article. This was due to the 20 fact that the measuring and depositing elements of the machine could not be readily removed and replaced by other elements adapted to measure and deposit articles of different volume and length. My present invention eliminates this necessity of having different machines by providing in the depositing mechanism removable valve elements as well as removable ejector plates which carry the depositing nozzles. Separate valve elements and corresponding nozzle plates for articles of different sizes may be obtained and readily introduced into the machine so that it will deposit a variety of 25 different size articles.

The foregoing and other objects of the invention, together with means whereby the same may be carried into effect, will best be understood from the following description of one form or embodiment thereof illustrated in the accompanying drawings.

In said drawings:

Fig. 1 is a fragmentary view partly in section of my improved measuring and depositing mechanism.

Fig. 2 is a transverse sectional view of the said mechanism also showing the part of the casing which is cut away in Fig. 1.

Fig. 3 is a fragmentary perspective view of my improved removable nipple or depositing plate.

Fig. 4 is a fragmentary perspective view of a removable sleeve of the valve mechanism shown in Figs. 1 and 2.

Fig. 5 is a similar view of the plunger carrying shaft used within the sleeve of the 60 valve mechanism shown in Figs. 1 and 2.

Fig. 6 is a view of a valve mechanism and nipple plate which can be substituted for the valve mechanism and nipple plate shown in Fig. 1, the mechanism shown being used 65 for depositing articles of greater size and length.

Fig. 7 is a similar view of a valve mechanism and nipple plate for depositing articles of still greater size and length.

Fig. 8 is a fragmentary perspective view of the type of nipple or depositor plate used with the valve mechanisms shown in Figs. 6 and 7 in which there are elongated openings 70 to correspond with the size of the valve 75 mechanisms.

The valve mechanism comprising the present invention is adapted to be used in machines of the character shown in the Demerath patent in which there is a hopper or 80 reservoir similar to that shown at 11 in Fig. 2 of the drawings. The melted chocolate or other semi-liquid material which is to be deposited is placed in the reservoir and passes into the depositing mechanism through the outlet in the bottom of the reservoir. This outlet is through a valve 85 casing 12 at the bottom of the reservoir. The casing 12 contains a valve which is adapted to control the passage of the material in the reservoir through the casing and deposit the same through the nozzles 13 on to a suitable receiver or conveyor, indicated generally at A.

As shown in Figs. 1 and 2 the valve comprises an oscillating sleeve 14 fitted to the interior of the casing 12 and formed with one or more recesses 15, corresponding in number and arrangement to the nozzles 13 on a plate 19, said recesses being adapted as the sleeve is oscillated to communicate with the bottom of the reservoir 11 or with the nozzles 13. Journalled in the sleeve 14 is an oscillating shaft 16 having one or more radial plungers 17 operating in the recesses 15 in the sleeve 14. The plungers 17, as herein shown, comprise blades or ribs seated in grooves in the shaft 16 and secured in place by any convenient means such as the screws 18. The nozzles 13 are carried on 100 105 110

the removable plate 19 which is detachably secured to the under side of the casing 12. The plate 19 as clearly appears from Fig. 3 is provided with a raised portion or rib 20 extending from one face of the plate throughout substantially its entire length. The said rib 20 enters and closes a single discharge opening or slot provided in the lower side of the casing 12 which opening 10 extends substantially the full length of the casing so as to communicate with all of the recesses 15 irrespective of the number, size, and arrangement of the latter in the particular valve employed. The upper side 21 15 of the rib 20 is a concave surface to match the periphery of the cylindrical sleeve 14. Openings 22 of a number, arrangement, and capacity to correspond with the recesses 15 in the sleeve 14 are provided through the 20 plate 19 and the rib 20, the construction being such that the several openings 22 will receive the material from the several recesses 15 respectively, said material passing through the said openings and the nipples 25 13 on to the said carrier. In operation the sleeve 14 is oscillated to direct the recesses 15 alternately into communication with the reservoir 11 and the nozzles 13. The shaft 16 is also periodically oscillated to 30 cause relative movement of the plungers 17 in said recesses between the end walls of the latter whereby measured quantities of plastic material such, for example, as to form the chocolate buds shown in Figs. 1 35 and 2, are alternately drawn from the reservoir into the recesses 15 and then expelled from the latter through the openings 22 in the plate 19 and the nozzles 13.

As already stated, it has been necessary 40 in the past to provide a separate machine for each different size article which is to be deposited. To overcome this difficulty the casing 12 as herein shown is constructed to permit the ready introduction of valve 45 mechanisms and nozzle plates of different capacities, such for example as that shown in Figs. 1 and 2 which is adapted to deposit candy drops or articles such as chocolate buds, as well as the valve mechanisms shown in 50 Figs. 6 and 7 which deposit articles such as chocolate bars of varying size and length. The removable valve elements are inserted and removed from the casing 12 through one end thereof. The nozzle plates 19 are 55 detachably fastened to the bottom of the casing 12 in any convenient manner such as by the screws 23. As already described and shown in Figs. 1 to 3, the valve mechanism suitable for depositing candy drops such as chocolate buds is provided with round 60 openings 22 and similar nozzles, there being an opening and nozzle for each of the recesses in the valve sleeve. In Fig. 6 is shown valve mechanism suitable for use 65 in depositing larger quantities of material,

as into molds B, the plungers 17^a on the shaft 16^a and the recesses 15^a in the sleeve 14^a being of correspondingly larger size and capacity, but said parts being otherwise adapted for reception in the valve 70 casing 12. The nozzle or depositor plate 19^a which is adapted for use with this valve mechanism is of the type shown in Fig. 8 in which the rib 20^a is cut away to provide the elongated openings 22^a which correspond in size to the recesses in the sleeve 14^a, said plate being otherwise adapted for attachment to the valve casing in substitution for the plate 19. The mechanism shown in Fig. 7 is designed to 80 deposit still larger quantities of material, as in the production of chocolate bars, the recesses 15^b in the sleeve 14^b, the plungers 17^b on the shaft 16^b, and the openings 22^b in the plate 19^b being correspondingly enlarged, but the construction being otherwise substantially identical with that shown in Fig. 6.

The above described construction of valve casing and the removable valve mechanisms and nozzle or depositor plates permit the machine to be readily converted from use for making one type of article to a machine for making an article of entirely different size and shape. 95

What I claim is:

1. In a depositor for plastic material having a reservoir for the material, valve mechanism comprising a valve casing communicating with said reservoir, a removable valve in said casing comprising a sleeve having a plurality of spaced recesses therein to receive measured quantities of the material from said reservoir, a shaft within the cylindrical sleeve, a plurality of radial plungers on said shaft one for each recess in the cylindrical sleeve, said casing having a slot extending substantially the full length thereof, and a removable plate having a rib filling the slot in said casing, and nozzle openings through said plate and rib for each of said sleeve recesses. 100

2. In a depositor for plastic material having a reservoir for the material, valve mechanism comprising a valve casing communicating with said reservoir, a removable measuring valve in said casing having a plurality of recesses therein to receive measured quantities of the material, said casing having a single discharge opening communicating with all of said recesses, and a plate removably secured to said casing, said plate having a projecting rib filling the discharge opening in said casing and itself provided with a plurality of discharge openings corresponding in number, arrangement, and capacity to the recesses in said valve. 110

3. In a depositor for plastic material having a reservoir for the material, valve 120

mechanism comprising a valve casing communicating with said reservoir, a removable measuring valve in said casing having a plurality of recesses therein to receive measured quantities of the material, said casing having a single discharge opening communicating with all of said recesses, and a plate removably secured to said casing,

said plate having a portion closing the discharge opening in said casing and itself 10 provided with a plurality of discharge openings corresponding in number, arrangement, and capacity to the recesses in said valve.

In testimony whereof I affix my signature.

ROBERT S. HISLOP.
